WORK HOLDER

Hans Zähner, Landquart, Switzerland

Application February 9, 1951, Serial No. 210,208
In Switzerland February 10, 1950

2 Claims. (Cl. 81—33)

1

The present invention relates to a work holder with a threaded spindle rotatably supported in a frame formed, for instance, as a casing, on which spindle a nut is carried so as to be longitudinally displaceable. On the frame, fixing members are also provided, thus making it possible to fix the work holder, to a table top for example.

The work holder according to the invention is designed in such a way that cheeks projecting in different directions are arranged on the frame and on the nut on the threaded spindle.

In the accompanying drawing some forms of execution of the object of the invention are illustrated by way of example, where:

Fig. 1 shows a side view, with a part in longitudinal section,

Fig. 2 shows a section on the line II—II of Fig. 1,

Fig. 3 shows a partial longitudinal section, an auxiliary jaw being added to one side of a spindle-carried nut.

Fig. 4 shows a side view similar to Figure 3, but substitutes a modified auxiliary jaw.

The work holder illustrated in Figs. 1—3 has a frame 1 in the form of a casing and made of cast-iron or sectional iron or light metal, the frame carrying a laterally arranged clamping or supporting plate 2. On the same side of the frame 1 as the plate 2, but at some distance from it, lugs 3 are fitted in which clamping screws 4 are held. By these latter screws it is possible to clamp the work holder firmly to a table top 5. The frame 1 is open downwards and upwards. Through it, there passes a spindle 6, which is provided in its middle part 7 with a square thread and is rotatable in the frame 1, but supported indisplaceably in the frame. At one end the spindle carries a handcrank 8 by means of which it can be rotated, whilst the opposite end is provided with an opening 9 for taking a drill or screwdriver (not illustrated). This drill or screwdriver can be secured in its working position by means of a clamping screw 10. In the illustrated example, the spindle 6 is formed in two parts, in that it carries on its free end a sleeve 11, to which it is connected by a rivet 12. The spindle 6 could, of course, also be made in one single part, and other means could be provided for fixing the drill.

On the frame 1, cheeks 13, 14 firmly connected to it are provided, the cheek 14 projecting in the axial direction beyond the frame 1. On the middle part 7 of the spindle a nut 15 can be displaced longitudinally but cannot rotate. To this nut a cheek 14' having a base portion extend-

2

ing in an axial direction along the frame 1 is firmly connected, this cheek cooperating with the cheek 14. On the other hand, a cheek 13' is detachably connected to the nut 15, in that a nose 16 engages behind a projection 17 on the nut 15. The cheek 13' cooperates with the cheek 13 permanently connected to the casing 1 and projecting transversely of said casing. Cheeks 13' of different shapes can be fitted to the threaded nut 15. Thus Fig. 4 for example shows a cheek 13'' with a fairly long bar 20. This execution makes it possible to fix very large workpieces. The tool according to Figs. 1—4 may be used as a general service clamp, the objects which are to be clamped together being gripped between the cheeks 13 and 13' or 13''.

The illustrated tool is capable of multiple applications. It is, for example, possible to clamp a saw between the cheeks 14, 14' and then sharpen the teeth. In consequence of the illustrated and described form of the cheeks 14, 14' the fixing of this saw will in no way be impeded by the frame 1. Just as desired, the whole tool can then be fixed to the table top in such a way that the saw hangs down beside the table top or lies along it.

With the variant according to Fig. 4 it is possible to fix comparatively big workpieces, for instance boards and rails, whilst the cheeks 13, 13' according to Fig. 3 ensure perfect fixing of very small workpieces. The tool may also be used as general service clamp and, as mentioned above, as drill or as screwdriver when the corresponding tool is fixed in the hole 9 (Fig. 1).

What I claim is:

1. A work holder including a longitudinally extending frame having parallel spaced side walls and end walls, a threaded spindle extending between and parallel to said side walls and means in said end walls for rotatably supporting said spindle, means attached to one end of said spindle for rotating the latter, means on one of said side walls for attaching the frame to a supporting member, a cheek secured on one of said end walls, a nut on said threaded spindle arranged to move axially of the latter when the spindle is rotated, an elongate bar having one end secured on said nut, said bar extending parallel to said threaded spindle and having its other end positioned beyond the other end wall of said frame, and said other end of said bar carrying a cheek confronting the cheek on said one end wall.
2. A work holder including a longitudinally extending frame having parallel spaced side walls

55

and end walls, a threaded spindle extending between and parallel to said side walls and means in said end walls for rotatably supporting said spindle, means attached to one end of said spindle for rotating the latter, means on one of said side walls for attaching the frame to a supporting member, a cheek secured on one of said end walls, a nut on said threaded spindle arranged to move axially of the latter when the spindle is rotated, an elongate bar having one end secured on said nut, said bar extending parallel to said threaded spindle and having its other end positioned beyond the other end wall of said frame, said other end of said bar carrying a cheek confronting the cheek on said one 15

4
end wall, and means for detachably securing said bar to said nut.

HANS ZÄHNER.
